(57) **CLAIM**

The ornamental design for front and rear fenders, as shown and described.

DESCRIPTION

FIG. 1 is a top right rear perspective view of a motorcycle showing the ornamental design of the exterior surfaces of the front and rear fenders.

FIG. 2 is a right orthogonal view thereof.

FIG. 3 is a top right rear perspective view of a rear fender in relation to a rear wheel.

FIG. 4 is a top right front perspective view of a front fender in relation to a front wheel.

FIG. 5 is a top left rear perspective view of a front fender in relation to a front wheel.

FIG. 6 is a right orthogonal view of a front fender.

FIG. 7 is a left orthogonal view thereof.

FIG. 8 is a front orthogonal view thereof.

FIG. 9 is a rear orthogonal view thereof.

FIG. 10 is a top orthogonal view thereof.

FIG. 11 is a bottom orthogonal view thereof.

FIG. 12 is a left orthogonal view of a rear fender.

FIG. 13 is a right orthogonal view thereof.

FIG. 14 is a top orthogonal view of a rear fender.

FIG. 15 is a bottom orthogonal view thereof.

FIG. 16 is a rear orthogonal view thereof; and,

FIG. 17 is a front orthogonal view thereof.

The single dashed lines represent parts of a motorcycle and form no part of the claim. The dash-dot lines represent the mounting interface of a front fender and form no part of the claim.
